UNITED STATES PATENT OFFICE.

WILLIAM L. PEARCE, OF VOLTA, CALIFORNIA.

CAN-WASHER.

No. 880,162.

Specification of Letters Patent.

Patented Feb. 25, 1908.

Application filed May 9, 1906. Serial No. 315,968.

To all whom it may concern:

Be it known that I, WILLIAM L. PEARCE, a citizen of the United States, residing at Volta, in the county of Merced, State of California, have invented certain new and useful Improvements in Can-Washers; and I do hereby declare the following to be a full, clear, and exact description of the invention, such as will enable others skilled in the art to 10 which it appertains to make and use the same.

This invention relates to can washers and more particularly to that class which are designed to be held and operated by hand.

15 The primary feature of the invention resides in the provision of a frame for the journaling of the hand-crank and brush-shaft, which will be formed integral with the shank of the handle of the device and by simply 20 bending the said shank, thereby forming an inexpensive and easily manufactured construction.

A further object of the invention resides in the provision of a device of this nature in 25 which the brush-shaft may be quickly and easily removed for the mounting of a shorter or longer shaft as may be desired.

In the accompanying drawings: Figure 1 is 30 a front elevation of the invention. Fig. 2 is a detail sectional view.

Referring more specifically to the drawings, the numeral 5 denotes a rod which forms the shank of the handle of the cleaner and which is provided at its upper end with a handle 6. 35 The lower portion of the rod 5 is flattened and is bent laterally as at 7 and upwardly as at 8, the extreme end portion of the flattened end of the rod 5 being bent laterally as at 9 at right angles to the upwardly bent portion 8 40 thereof and directly above and parallel to the portion 7 and being secured at its extreme end to the rod 5 by welding or any other suitable means. The portions 7 and 9 of the frame thus formed are provided with alining 45 openings through which is engaged the upper end of a brush-shaft 10, the extreme upper end of the shaft being screw-threaded as at 11 for the engagement of a nut 12 therewith which bears against the upper face of the 50 portion 9 and serves to prevent accidental removal of the shaft from the frame. Keyed

to the shaft 10 directly above the laterally bent portion 7 of the frame is a bevel gear 13 and journaled in one of the vertical portions of the frame is a crank 14 to which is keyed a 55 bevel gear 15 which meshes with the bevel gear 13 on the shaft 10, the said crank 14 being provided with a handle 16 by means of which it may be rotated.

Adjacent its lower end the brush-shaft 10 60 is provided with an integral collar 17 between which and a nut 18 is engaged the core or hub of a brush 19.

From the foregoing, it will be seen that by forming the frame of the device integral with 65 the handle-shank 5 by bending the said shank an extremely simple and inexpensive means for mounting the brush-shaft and operating gear therefor is provided.

What is claimed is:

70 A can washer of the class described consisting of a handle shank which is flattened and slightly offset at the beginning of its flattened portion, the said flattened portion being bent to extend downwardly and in a 75 plane parallel with the handle shank proper, thence horizontally, thence vertically, this latter portion being parallel with the first mentioned downwardly bent portion, thence horizontally and secured at its extreme end 80 to the handle shank at the offset therein whereby a rectangular frame is formed, a brush shaft journaled in the two horizontal portions of this frame, a nut engaged upon the upper end of the shaft and resting upon 85 the upper horizontal portion, a gear splined to the shaft and resting upon the lower horizontal portion, a crank shaft journaled in the first mentioned vertically bent portion, a gear carried by the said crank shaft 90 for rotation therewith, said gear being in mesh with the first mentioned gear and rotating against the said vertically extending portion in which the crank shaft is journaled, and a transverse handle fixed at the upper 95 end of the handle shank.

In testimony whereof, I affix my signature, in presence of two witnesses.

WILLIAM L. PEARCE.
